PHOTOGRAPHIC FILM PROCESSOR

Ralph M. Vigna, Rochester, N.Y., assignor to
Eastman Kodak Company, Rochester, N.Y.

Filed Apr. 25, 1973, Ser. No. 354,277

Term of patent 14 years

Int. Cl. D16—04
U.S. Cl. D61—1 Q

FIG. 1

FIG. 2

FIG. 3

FIG. 4

FIG. 1 is a front isometric view of a photographic film processor showing my new design;

FIG. 2 is a rear isometric view thereof;

FIG. 3 is a front isometric view of another embodiment of my new design of FIG. 1;

FIG. 4 is a rear isometric view thereof.

I claim:

The ornamental design for a photographic film processor, as shown and described.
